UNITED STATES PATENT OFFICE.

SAMUEL PIERCE, OF TROY, NEW YORK.

FURNACE.

Specification of Letters Patent No. 22,670, dated January 18, 1859.

To all whom it may concern:

Be it known that I, SAMUEL PIERCE, of Troy, in the county of Rensselaer and State of New York, have invented certain new and 5 useful Improvements in Constructing Air-Heating Furnaces; and I do hereby declare that the following is a full, clear, and exact description of the same, reference being had to the annexed drawings, making part of 10 this specification, in which—

Figure 1 is a perspective view, Fig. 2 is a longitudinal section, and Fig. 3 is a transverse section taken at the line X X of Fig. 2, the same letters having reference to like 15 parts in each of the figures.

The nature of my invention, or that which distinguishes it from other improvements heretofore made in air heating furnaces, consists in the peculiar manner in which I construct and arrange the radiating surfaces of the air heating chambers or channels, which consists of a series of iron plates having duly arranged upon their radiating surfaces numerous stems or radiating points, which, 25 when the plates are arranged in a series upon and around the outer surface of the fire box and fire chamber of the furnace, with the outer casing properly adjusted over them, as hereafter fully described, form a series of air 30 heating chambers or channels, whose sides are thickly studded with radiating points or stems projecting from the sides and partially filling the channels in such a manner that the cold air in its course through the channel, impinges upon the first radiating points 35 or stems, and is partially reverberated and diverged upon other radiating points in the course of the channel until the whole volume or current of air passing through the 40 channel has obtained an equal degree of heat, which is absorbed with the greatest facility, from the very large amount of radiating surface presented by this mode of construction, and further my improvement consists in the arrangement of a series of plane 45 radiating, or, of a series of corrugated radiating plates, in combination with a horizontal fire box and fire chamber, and the outer casing as hereafter described.

50 The construction of my improved air heating furnace is as follows, viz:

A is a horizontal fire box, B the horizontal fire chamber C the smoke pipe D the ash pit, E the grate bars, F front plate.

55 The top plate G, of the horizontal fire box and fire chamber is constructed in a wave or

corrugated shape in order to give strength to the casting and increase the extent of radiating surfaces, also to form beds or bearings for a series of heat radiating plates. 49

I, is the under plate of the furnace.

J, J, is a series of segment or horse shoe shaped plates, upon the surfaces of which are cast or otherwise formed, numerous radiating points or stems (a a a); these heat radiating plates are duly arranged in a series upon and around the outer surface of the plate G in the manner substantially as shown in the drawings; thus forming a series of air heating chambers or channels 79 (d d). These segment or horse-shoe shaped plates, as will be seen by referring to the drawing, have their edges resting upon the fire-plate (G), the edges of the plates being in the grooves of the plate (G). The segment plates are detachable or removable. The series of points or projections from these plates form on both sides radiating surfaces and in this respect differ from other plates with projections where the one side of 39 the plate is an absorbing and the other side a radiating surface. These plates in all their surfaces and projections are radiating. 75

K is the outer plate or casing of the heat radiating surfaces and air heating chambers, 85 and has a series of openings (e e) at its top part, one for each air heating chamber, through which the hot air passes into the receiving chamber, from whence it is conducted where needed by pipes or flues in the 90 usual manner.

The furnace is set in brick work, as shown by the red lines in the drawings, and has the usual appendages for imparting the necessary moisture and purity to the heated air 95 in the manner well known to constructors and setters of air heating furnaces.

The operation of the furnace is as follows: Fire having been properly ignited in the fire box, cold air is received by the supply 100 pipe at the back end of the furnace, in direction as shown by the arrow (f) the heat of the furnace rarefying and expanding the cold air, causes an ascending draft around the sides and surfaces of the furnace, and into the heating chambers or channels (d d) 105 as shown by the arrows (g) where the current of air is impinged upon numerous radiating points and partially reverberated, diverged, from and to, other heat radiating points and surfaces in its course through the heating channel, until its whole volume has 110

become of an equal temperature, when it is permitted to pass by the usual conducting pipes to the apartments or purposes for which it is needed.

5 The peculiar advantages of my improved furnace, are: in its perfect adaptability to any description of anthracite or bituminous coals, wood or peat. From my improved mode of constructing the fire box 10 and fire chamber back of it, in horizontal positions, it is especially adapted to burning fuel containing large quantities of sulfurous, or bituminous, or resinous qualities. The fire box and fire chamber being so constructed 15 that the sulfurous, bituminous, and resinous matters as they are converted into gases by the action of the fire ascend to the top of the fire chamber, from whence they are reverberated downward, as shown by the 20 directions of the arrows Fig. 2, until the combustible gases become so heated that they ignite and are mainly consumed before entering the smoke pipe, thereby saving much combustible matter which would otherwise escape, and further, my mode of constructing 25 the fire chamber requires but one fire flue, and that can be of good size, so that there is little cleaning of flues required and no liability to choking of flues with soot, or 30 escape of noxious or carbonaceous gases from the fire chamber into the air chamber and channels.

A good series of air heating chambers could be made by omitting the heat radiat-

ing points on the radiating plates *J*, *J*, thereby leaving a free passage to the air, but still presenting a great degree of heating surface to the current of air; or, the heat radiating plates *J*, *J*, could be further modified by omitting the points or stems, and forming the plates in a vertically corrugated shape, which would give them a greater radiating surface than the plane plates, and also give a deflecting motion from side to side to the air in passing through the channels, so that it is a longer time in its passage, and is more equally heated in all parts of its volume.

Having fully described my invention what I claim as new therein, and desire to secure by Letters Patent, is:

1. The series of detachable or removable heat radiating plates *J*, *J*, constructed with points or stems (*a a*) projecting from their surfaces both of the surfaces being radiating surfaces, in the manner and for the purposes substantially as herein described.

2. Also, in combination with a horizontal fire box and fire chamber, and the outer casting *K*, I claim a series of plane heat radiating plates; or, a series of corrugated heat radiating plates, arranged substantially in the manner and for the purposes as herein described.

SAMUEL PIERCE.
